UNITED STATES PATENT OFFICE

EDWARD J. YETTER, OF DENVER, COLORADO

GARTER OR STOCKING SUPPORTER

Application filed June 8, 1928. Serial No. 283,827.

My invention relates to improvements in stocking supporters, and particularly to stocking supporters for men's use.

The main object of the invention is to provide a stocking supporter, comprising an adjustable band which is worn above the knee, and a depending strap pivotally connected thereto and having a suitable fastener on its free end for connection to the stocking in the usual manner, the pivotal connection of the strap with the band permitting the free bending of the leg without a pulling action on the band, and the wearing of the band above the knee making it unnecessary to fasten the same so tightly as to cause discomfort.

These and other objects are accomplished by the character of supporter illustrated in the accompanying drawings, in which:

Fig. 1 is a side view of a stocking supporter arranged according to my invention, and showing the same as it appears in actual use.

Fig. 2 is a similar view showing a slight change in the construction, and

Fig. 3 is a top view of the supporter shown in Fig. 1.

Men's garters or stocking supporters in present use are often uncomfortable and therefore unsatisfactory for the reason, that being worn above the calf of the leg, they must, in many cases, be secured, tightly to prevent slipping, thereby causing considerable discomfort to the wearer. The present invention, however, eliminates these objectionable features by providing a garter which is worn above the knee, and therefore does not need to be so tightly secured upon the leg as to bind thereon or be prevented from slipping; which adjusts itself to the movements of the leg without either tightening or relaxing the pull on the stocking and which, therefore, can be worn without the least discomfort.

Referring to the accompanying drawings—

The numeral 1 designates the band or garter portion of the supporter, which is preferably made of the usual elastic material, one end of which is looped or folded

upon itself and is secured to the center bar of a common form take-up 2, which is slidably mounted on the band, so that by moving the take-up the band can be increased or diminished in size to suit the leg of the wearer. To this folded end of the band is attached a common form of catch 3, comprising a bar which is secured in the folded end of the band, and a V-shaped hook 4. The opposite end of the band has stitched thereto a short leather strip 5, which gives the necessary body and strength to this end of the strap, and a headed stud or button 6 is secured to the outer end portion of this strip, which is adapted to engage the hook 4 when the band is secured upon the leg. The parts thus far described are in common use, and any other form of fastening device, may be employed, as this feature, in itself, forms no part of my invention.

Upon the opposite end portion of the leather strip 5 is secured a headed stud 7, upon which is pivotally mounted a connecting member 8, which may be of any suitable character, but which, in the present instance is in the form of a ring of stout wire which is bent to form an eye 9, which engages the stud 7 so as to swing thereon, without becoming detached therefrom, and short parallel side members which terminate in a transverse cross bar 10. To the cross bar 10 is secured the folded end portion of a supporting strip 11, which is preferably elastic material, and the end of the folded portion is connected to a take-up 12, which is slidably mounted on the supporting strip in the usual manner, so that the said strip may be lengthened or shortened, as may be required. The lower end of the supporting strip is provided with the common form of fastening device 13 for gripping the top portion of the stocking. A piece of suitable material is stitched to the under side of that end of the band 1 to which the leather strip 5 is secured, and this material forms a shield 14, which lies beneath the hook member 3 and the connecting member 8, and prevents contact of these parts with the leg. It will thus be seen, that when the band 1 is secured

around the leg above the knee, and the supporter 11 secured to the top of the stocking, the stocking will be held in any position of the leg, without any pulling strain on the band more than is required to support the stocking.

In Fig. 2 of the drawings is shown a slight change over the construction shown in Fig. 1. In this arrangement, the hook member 3 and take-up 2 are on the opposite end of the band 1A from that shown in Fig. 1, and in place of the leather strip 5, I employ a leather strip or tab 5A, which extends down a short distance below the lower edge of the band 1A, and this extended end of the tab is provided with a headed stud 7A, to which the connecting member 8 of the supporter 11 is pivotally attached, the same as in Fig. 1. By this arrangement, the stud 7A is positioned substantially in line with the axis of the knee joint, so that the said stud will always be the same distance from the connection of the fastener 13 with the top of the stocking in all positions of the leg, thus preventing any strain upon the band or garter, greater than the original pulling strain on the band when the stocking is secured to the supporter.

A shield 14A is secured to the opposite side of the end portion of the band 1A, from the tap 5A, and lies beneath the hook member 3 and the connecting member 8, to prevent contact of these parts with the leg.

While my improved garter or stocking supporter is embodied in the construction set forth in the accompanying drawings, it will be apparent that various changes in this construction can be made without departing from the spirit of the invention.

Having described my invention, what I claim as new and desire to secure by Letters Patent, is:—

A stocking supporter, comprising a leg band adapted to be worn above the knee, having a tab stitched upon one end thereof at right angles to the band, one end of said tab extending below the band, a headed stud on the extended end of said tab in line with the knee joint, an extensible strap having a fixture on one end which is pivotally connected to said headed stud, and a stocking-gripping clasp on its opposite end; a fastening element on said tab in line with the center of the width of the band and in vertical line with the headed stud, and a fixture on the opposite end of the band for connection with said fastening element.

In testimony whereof, I affix my signature.

EDWARD J. YETTER.
